MACHINE FOR CEMENTING SOLES TO SHOES

Pineus Brauner, Haverhill, Mass.

Application December 11, 1934, Serial No. 756,965

16 Claims. (Cl. 12—37)

This invention relates to machines for use in manufacturing shoes and particularly to machines having a number of inflatable shoe presses or jacks each adapted to hold a sole firmly against a shoe bottom while the cement sets. The machine illustrated is intended primarily for use in the manufacture of shoes in which cement alone is relied upon to permanently attach the outer sole to a shoe.

When cement is employed to permanently secure the sole to a shoe it is important that the adhesive covered portions of the sole be firmly pressed against the bottom of the shoe, and if a cement which does not grip immediately is used it is important that the sole be held firmly in place throughout the one or more minutes required for the cement to set.

It has been proposed heretofore to provide shoe presses or jacks having an inflatable pad for pressing the sole firmly against the bottom of a shoe, and in order to speed up production it has been suggested heretofore to provide a rotating wheel or table having a number of inflatable jacks and provided with valve means at the hub of the wheel adapted to be controlled by the rotation of the wheel to inflate and deflate the jacks, so that each jack will be held inflated as the wheel rotates throughout the greater part of a complete circle. Difficulty has been experienced heretofore however in providing a rotating valve at the hub of the wheel which will not leak under the relatively high pressure employed to inflate the pads, and which will permit the wheel to rotate freely. This difficulty in securing a tight valve has been largely due to the fact that when the non-rotating part of the valve is formed rigid or integral with the wheel supporting axle any slight play or inaccuracy in the wheel bearing tends to disturb the seating of the valve parts and causes leakage, and if the valve is tightened to prevent such leakage the increased friction makes the wheel hard to turn.

One important feature of the present invention therefore resides in a valve which overcomes this difficulty and more particularly in a construction whereby the non-rotating part of the valve is floatingly connected to the fixed wheel axle and is held seated in the portion of the valve that rotates with the wheel without carrying any load, and as a result a tight valve seat is secured which is not disturbed by the rotation of the wheel or inaccuracies in the wheel bearing.

The time required to remove a shoe with the sole attached from a jack and insert another shoe is only a small fraction of the time required

for the cement commonly used to set, so that a skilled operator can jack and unjack a number of shoes during the period that a shoe should be held in a jack while the cement sets. It has therefore been proposed heretofore to provide the jack supporting wheel with a relatively large number of jacks, but this has resulted in the use of a large unwieldy wheel.

Another important feature of the invention therefore resides in a sole cementing machine of the rotating wheel type but which is so constructed that a relatively large number of jacks can be mounted upon a much smaller and lighter wheel than in the construction proposed heretofore, and in which jacks extend radially outwardly beyond the periphery of the wheel and frontwardly from the plane of the wheel so that the shoes can be more readily placed in and removed from the jacks.

A further feature resides in pedal controlled means that cooperates with the jack supporting wheel whereby when a jack is in position to be controlled from the operating station it may be either inflated or deflated at the will of the operator by operating one or the other of a pair of foot pedals. This is important because it is necessary that the sole be accurately applied to the shoe preparatory to cementing it in place and this foot controlled means enables the operator to quickly inflate the jack while the shoe and sole are held in place, and to quickly deflate the jack in case the shoe parts are not properly positioned in the jack. Furthermore as a result of these foot pedals for controlling the inflation of a jack at the operating station, shoes may be placed in the jacks and removed therefrom while the wheel rotates continuously at a uniform speed.

Still a further feature of the invention resides in the construction of the wheel for supporting the jacks whereby the pipes for inflating the jacks are concealed in the spokes and cast parts of the wheel where they are protected and out of the way, and another feature resides in novel means for completing the pipe connections between a jack and the valve at the hub of the wheel as the jack is secured to the wheel.

Other features of the invention and novel combination of parts in addition to the above will be hereinafter described in connection with the accompanying drawings which illustrate one good, practical form of the invention.

In the drawings:

Fig. 12 is an end view of the device of Fig. 11 and;

Fig. 13 is a sectional view taken on the line 13—13 of Fig. 11.

In the embodiment of the invention illustrated in the drawings the shoe presses or jacks 10 are provided with supporting brackets 11 adapted to be secured by bolts 12 to bosses 13 formed on the rim 14 of a jack supporting wheel. This wheel is shown as having five spokes 15 extending from the hub 16 of the wheel to the rim 14. The wheel and jacks are so constructed that the jacks are supported by the bracket 11 so that they extend radially outwardly a substantial distance from the rim of the wheel and project frontwardly a substantial distance from the plane of the wheel. This arrangement permits a relatively large number of jacks (thirty in the present case) to be carried by a wheel that is less than four feet in diameter, and positions the jacks frontwardly of the plane of the wheel far enough to permit the machine operator engaged in placing the shoes in the jacks to look downward upon the shoe from a position near the hub of the wheel to see if the sole of the shoe is correctly held against the bottom of the shoe when the shoe supporting pad or bag 17 is inflated.

The wheel which carries the jacks is supported in the construction shown to rotate in a vertical plane by a hollow column or casing 18 adapted to support the wheel at such a height from the floor that when a jack 10 lies directly below the axis of the wheel as shown in Fig. 2 it will be just high enough from the floor to be most convenient for the operator engaged in placing a shoe S in or removing it from this jack. The casing 18 has the base 19, and secured to a side wall of the upper part of the casing is the wheel supporting axle 20. This axle is preferably tapered as shown and is provided with the roller bearings 21 and 22 and the outer end of the axle is threaded as at 23. The axle has a supporting flange 24 that may be bolted or otherwise secured to the casing 18.

The jack supporting wheel is so designed that its hub 16 spokes 15 and rim 14 may be formed as an integral casting, the spokes being connected between each other near the hub by the flanges 25, and the portion of the wheel between the hub 16 and flanges 25 is preferably made hollow as are also the spokes 15 and rim 14 to reduce the weight of the wheel and to receive the jack inflating pipes to be described.

It is desirable to provide means for slowly ro-

tating the wheel in the direction indicated by the arrow in Fig. 1 at a speed which will permit the machine operator to remove one shoe from a jack and insert another shoe without stopping the wheel, as each jack passes through the range 5 of its lowest position. The wheel is slowly rotated in the construction shown by securing to the rear face of the wheel a ring gear 26 adapted to be driven by a pinion 27 secured to a shaft 28 journaled in the casing 18. The shaft 28 is driven through the bevel gears 29 from a vertical shaft 30. The shaft 30 is driven by an electric motor 31 and the reducing gears within the gear casing 32. The starting and stopping of the motor 31 is controlled by the switch 33 connected to the 15 motor by the conductors 34.

The machine of the present invention is designed more particularly for use in cementing the outer soles permanently to shoes when a cement is used which does not grip immediately but requires an interval of time for the cement to set, and by employing a wheel carrying a large number of jacks, each jack may be kept inflated while it rotates through the greater part of a complete circle and the other jacks of the wheel 25 have the shoes therein changed.

One important feature of the present invention resides in the means for controlling the inflation and deflation of the bags 17 of the various jacks, as the wheel rotates, and the means shown to this end will now be described. The wheel has cast or otherwise secured in its front face about the axis of rotation a ring 35 which may be formed of steel and this ring is provided with pipe receiving holes adapted to receive the jack inflating pipes 36 one for each of the thirty jacks. The ends of these pipes may be welded or otherwise secured in the ring 35 to provide air tight joints therebetween and the outer face of the ring may be ground to provide 40 a smooth true surface.

To the outer face of the ring 35 is secured the ring-like valve member 37 which is secured to the ring by the bolts 38, and a gasket 39 is provided between the members 35 and 37 to prevent leakage of the compressed air from between them. The valve member 37 is bored or otherwise provided with the air passages 40 which align with the ends of the pipes 36 in the ring 35. The passages 40 communicate with ports 41 and 42 arranged in two rows in the inner wall of the valve member 37 in staggered relation as best shown in Fig. 8. The pipes 36 are mounted in the hollow spokes 15 where they are protected and out of the way and they extend outwardly through a 55 spoke and within the hollow rim 14 to the jack receiving flanges 13 as will be apparent from Fig. 1, six pipes being provided in each spoke 15.

The jacks 10 are preferably constructed as shown in Figs. 1 and 2 of my application Serial 60 No. 753,263 filed November 16, 1934, and as will be apparent from said application each jack is provided with a tube 43 concealed in the casting and extending from the face of the bracket 11 that is bolted to the boss 13 to the bag stem 44 65 leading into the bag 17. A gasket 45 is preferably provided between the boss 13 and bracket 11 secured thereto. Each jack 10 is also provided with an overhanging arm 46 of the cantilever type and the outer end of which forms an abutment 70 for a last 47 when the shoe in which the last is placed is forced upwardly by the inflation of the bag 17. Each jack is further provided with a toe engaging member 48, all as more fully shown and described in said application. 75

The pipe connections so far described serve to supply compressed air from the outer valve member 37 to the bags 17 of the various jacks, and the means for supplying compressed air to and exhausting the ports of the valve member 37 will now be described. Compressed air from any suitable source of supply (not shown) is supplied by a pipe 49 to a bore 50 formed longitudinally of the fixed axle 20, and secured to the opposite end of this bore by the coupling 51 is a flexible pipe 52. Within the rotating valve member 37 is seated the non-rotating valve member 53 and compressed air is supplied to the ports 54 and 55 and connecting conduit 56 of the valve member 53 by the flexible pipe 52 connected to 53 by the coupling 57.

Since the air used to inflate the bags 17 is preferably supplied under relatively high pressure it is important that the non-rotating valve member 53 be held accurately seated in the rotating valve member 37, and to this end in the construction shown, the valve member 53 is accurately ground to fit the member 37 and is yieldingly held seated therein by a coiled spring 58 one end of which rests against an antifriction ball 59 which ball rests in a pocket 60 formed in a spider 61 that is seated in the outer end of the valve member 53 and is secured to this member by screws 62. The valve members 37 and 53 are enclosed in a cover 63 that is secured to the outer end of the member 37 by bolts 64 and the cover 63 has the valve covering skirt 65 extending towards the wheel. The central portion of the cover plate 63 has a threaded opening adapted to receive the bolt 66 against which the outer end of the spring 58 is seated and this bolt may be adjusted to vary the pressure of the spring upon the valve member 53.

The jack supporting wheel is retained upon its supporting axle 20 by a nut 67 that is provided upon the threaded end 23 of the axle, and the nut bears against a washer 68. The inner valve member 53 is floatingly connected to the axle 20 so that it is held from rotating by the axle, but is relieved from the weight of the wheel and is free to seat accurately in the valve member 37 under the action of the spring 58. This result is secured by providing on the axle 20 the washer 69 which is keyed to the axle so that it can not turn and is clamped between the nuts 67 and 70. The washer 69 has the slots 71 formed in its outer edge (see Fig. 10) to receive the inwardly projecting fingers 72 upon the valve member 53 so as to hold this member from rotating.

The mechanism so far described serves to supply compressed air from the supply pipe 49 to each jack as the port 41 or 42 controlling a jack is brought into alignment by the rotation of the wheel with a port 54 or 55, and the compressed air supplied to a jack through these aligned ports is prevented from being exhausted from the jack until the wheel has been turned through nearly a complete revolution. The air is exhausted from a jack when the wheel is rotated to align the port 41 or 42 with the exhaust groove 73 formed in the face of the valve member 53 a short distance from the ports 54 and 55. The groove 73 is preferably enlarged at 74 and 75 to allow a longer period of time in which the air might exhaust from the bags 17 as the wheel rotates.

It is important to thoroughly lubricate the operating surfaces of the valve members 37 and 53 and this is accomplished in accordance with the present invention by providing in the face of

the valve member 53 the grease receiving groove 76 to which grease is supplied through the conduits 77 from a grease cup 78 mounted on the spider 61. The cover of the grease cup may be tightened from time to time to feed grease to the bearing groove 76 by inserting a screw driver through any one of the openings 79 formed in the cover plate 63. It is desirable to feed grease to this bearing when the wheel and its cover plate 63 are turned to different positions relative to the non-rotating valve member 53. The cover plate 63 is therefore shown in Fig. 5 as provided with thirty holes 79 numbered in irregular order from 1 to 30 inclusive so that the screw driver used in tightening the cover of the grease cup 15 may be inserted in a different hole 79 upon each day of the month in the order shown by the numerals 1 to 30 opposite these holes.

When the jack supporting wheel is rotated continuously at a uniform speed as contemplated in the present case as the operator changes the shoes in the successive jacks, it is important that means be provided whereby he may quickly inflate a jack bag 17 as soon as a shoe is properly placed in the jack, and prevent the bag from being inflated before the shoe is properly placed in the jack. This is accomplished in accordance with the present invention by providing near the base of the machine the pedal control device 80 having the foot operable plunger 81 for supplying compressed air through the pipe 49 and aligned ports 41 and 54 or 42 and 55 to a particular bag 17, and also having the foot operable plunger 82 for exhausting air through these connections from the bag 17.

The construction of the device 80 is best shown in Fig. 13 in which air under pressure is supplied to the chamber 83 through the inlet port 84 from any suitable source of compressed air not shown. When the plunger 81 is depressed against the upward pressure of the spring 85 it will open the valve 86 and permit the compressed air to enter the upper chamber 87 and conduit 88. Communicating with an intermediate portion of the conduit 88 is the port 89 to which is connected the pipe 49 leading to the wheel axle. When it is desired to exhaust air from a bag 17 while the controlling ports 41 and 54 or 42 and 55 are aligned the plunger 82 is depressed against the pressure of the spring 90 to open the valve 91 so that the air from the bag 17 may enter the chamber 92 and exhaust into the atmosphere through the port 93. The pipe 49 and conduit 88 serve to inflate and deflate the bag 17 depending upon whether the plunger 81 or 82 is depressed, and the valves 86 and 91 are so arranged that the pressure of the compressed air against them tends to hold them seated.

It will be seen from the foregoing that the set of thirty jacks are supported by a comparatively small wheel and that these jacks are so supported from the wheel that the machine operator may quickly and accurately place the shoes in the jacks as the wheel is continuously rotating, and if a shoe is not properly positioned as a jack is inflated by stepping on the plunger 81, it may be immediately deflated by stepping on the plunger 82 to exhaust the air from the jack so that the sole may be properly positioned on the shoe and the jack inflated again. A particular jack is under the control of the foot plungers 81 and 82 only while it is moving through a small arc below the wheel axle and if it should be desired to exhaust the air from a jack before it is carried by 75

the wheel around to the position of the exhaust groove 13, the jack may be deflated by opening a hand valve 94 with which each jack is provided.

While in the construction shown the jack supporting wheel rotates in a vertical plane, this wheel may be supported, if desired, to rotate in a horizontal plane; and while the jacks shown are designed more particularly for use in permanently cementing soles in place, they may be employed simply to shape the soles to the bottom of the shoes, or to cement soles to the shoes when the cement is relied upon to hold a sole in place and keep it from creeping while the sole is being stitched to the shoe.

15 I claim:

1. A machine for cementing soles to shoes comprising in combination, a series of jacks each having an inflatable bag for pressing a sole against a shoe, a rotating wheel formed as a casting and 20 having a hub, hollow spokes and a rim all cast together, means for securing the jacks to said rim, and said wheel being provided with bag inflating pipes leading from the hub of the wheel through the hollow spokes and rim to the jacks 25 and positioned within the cast wheel structure where they are concealed and out of the way.

2. A machine for cementing soles to shoes comprising in combination, a series of jacks each having an inflatable bag for pressing a sole against 30 a shoe, a rotating wheel formed with a hub, hollow spokes and a rim, means for securing the jacks to said rim, and pipes for inflating said bag extending from the hub to the rim and positioned within said hollow spokes where they are entirely 35 concealed and out of the way.

3. A machine for cementing soles to shoes, comprising in combination, a series of jacks each having an inflatable bag, a supporting flange upon each jack, a pipe extending through the flange 40 and leading to the bag of the jack; a wheel having a supporting hub and a much larger annular rim for supporting the jacks, pipes extending outwardly from the hub through the rim, and means for mounting the jacks on the wheel by 45 securing said flanges to the rim so that the pipe in a flange aligns with a pipe extending through the rim and forms a communication therebetween through which the bag can be inflated.

4. A machine for cementing soles to shoes comprising in combination, a series of jacks each having an inflatable bag, a supporting flange upon each jack, a pipe extending through the flange and leading to the bag of the jack; a cast wheel having a hub, spokes and a rim, pipes cast in the 55 wheel and leading from the hub through the spokes to different points of the rim, and means for mounting the jacks on the wheel by securing said flanges to the rim so that the pipe in a flange aligns with a pipe in the rim and forms a continuous communication through which a jack bag may be inflated.

5. A machine for cementing soles to shoes comprising in combination, a series of jacks each having an inflatable bag for pressing a sole against a shoe, a wheel for supporting the jacks and provided with a hub, pipes leading from the hub of the wheel to the bags of the different jacks, and means for mounting the ends of these pipes in the hub so that compressed air may be supplied 65 successively to each of these pipes, comprising a metal ring secured in the hub and having the ends of said pipes tightly secured in holes formed in said ring.

6. In a machine of the class described in combination, a wheel provided with a series of air

confining means, pipes leading from the hub of the wheel to said means, a shaft for rotatably supporting the wheel, valve mechanism for controlling compressed air supplied to said means through said pipes including a valve part secured to the wheel to rotate therewith and provided with a central conical bore, a conical non-rotating part that fits said bore to form an air tight joint therebetween, and means for holding said non-rotating part seated in said bore and for floatingly holding the non-rotating part from rotating.

7. In a machine of the class described in combination, a wheel provided with a series of air confining means, pipes leading from the hub of the wheel to said means, a shaft for rotatably supporting the wheel, valve mechanism for controlling compressed air supplied to said means through said pipes, including a valve part secured to the wheel to rotate therewith and provided with a central conical bore that flares outwardly, a conical non-rotating part that fits said outwardly flaring bore to form an air tight joint therebetween, and means for holding said non-rotating part seated in said bore and for floatingly holding it from rotating.

8. A machine for cementing soles to shoes comprising in combination, a series of jacks each having an inflatable bag for pressing a sole against a shoe, a wheel for supporting the jacks and provided with pipes leading from its hub to the jack bags, a shaft for rotatably supporting the wheel, means for controlling the inflation of said bags from the hub through said pipes including a valve casing secured to the wheel to rotate therewith and provided with a central conical bore, a conical non-rotating part that fits said bore to form an air tight joint therebetween, means for yieldingly holding said part seated in said bore and for floatingly holding said part from rotating.

9. A machine for cementing soles to shoes comprising in combination, a series of jacks each having an inflatable bag for pressing a sole against a shoe, a wheel for supporting the jacks and provided with pipes leading from its hub to the jack bags, a shaft for rotatably supporting the wheel, means for controlling the inflation of said bags from the hub through said pipes including a valve casing secured to the wheel to rotate therewith and provided with a central conical bore, a conical non-rotating part that fits said bore to form an air tight joint therebetween, a front plate secured to the wheel over said non-rotating part, spring means confined between said front plate and said part to hold the latter yieldingly seated, and means for floatingly holding said part from rotating.

10. A machine for cementing soles to shoes, comprising in combination, a series of jacks each having an inflatable bag for pressing a sole against a shoe, a rotating wheel for supporting the jacks and provided with pipes leading from its hub to the jack bags, means for controlling the inflation of said bags from the hub through said pipes including a valve casing secured to the wheel to rotate therewith and provided with a central conical bore, a conical non-rotating part that fits said bore to form an air tight joint therebetween, a front plate secured to the wheel over said part to rotate with the wheel, spring means confined between the front plate and said part to hold the latter yieldingly seated, and an antifriction bearing at one end of said spring means.

11. A machine for cementing soles to shoes, comprising in combination, a series of jacks each hav-

- ing an inflatable bag for pressing a sole against a shoe, a wheel for supporting the jacks and provided with pipes leading from its hub to the jack bags, a shaft for rotatably supporting said wheel, means for controlling the inflation of said bags from the hub through said pipes including a valve casing secured to the wheel to rotate therewith and provided with a central conical bore, a conical non-rotating part that fits said bore to form an air tight joint therebetween, and means for floatingly connecting said non-rotating part to said shaft to hold the former from rotating. 10
12. A machine for cementing soles to shoes, comprising in combination, a series of jacks each having an inflatable bag for pressing a sole against a shoe, a wheel for supporting the jacks and provided with pipes leading from its hub to the jack bags, a shaft for rotatably supporting said wheel, means for controlling the inflation of said bags from the hub through said pipes including a valve casing secured to the wheel to rotate therewith and provided with a central conical bore, a conical non-rotating part that fits said bore to form an air tight joint therebetween, means for floatingly connecting said non-rotating part to said shaft to hold the former from rotating, and a flexible tube leading from said shaft to said floating part to supply compressed air from the former to the latter. 20
13. In a machine of the class described in combination, a wheel for supporting means using compressed air, a shaft for rotatably supporting the wheel, means for controlling the supply of compressed air to said first mentioned means including a valve casing secured to the wheel to rotate therewith and provided with a central conical bore, a conical non-rotating part that fits said bore to form an air tight joint therebetween, means for floatingly connecting said non-rotating part to said shaft to hold the former from rotating, and a flexible tube leading from said shaft to said part to supply compressed air from the former to the latter. 30
14. In a machine of the class described in combination, a wheel for supporting means using compressed air, a shaft for rotatably supporting the
- wheel, means for controlling the supply of compressed air to said first mentioned means including a valve casing secured to the wheel to rotate therewith and provided with a central conical bore, a conical non-rotating part that fits said bore to form an air tight joint therebetween, a front plate secured to said wheel over said non-rotating part, spring means confined between the front plate and said part for holding the latter seated, and an antifriction bearing at one end of said spring means. 10
15. In a machine of the class described in combination, a wheel provided with a series of air confining means, pipes leading from the hub portion of the wheel to said means, a shaft for rotatably supporting the wheel, valve mechanism for controlling compressed air supplied to said means through said pipes, including a valve casing upon the wheel to rotate therewith and provided with a conical central bore that flares outwardly away from the plane of the wheel, a tapered valve part non-rotatably but movably secured to said shaft and adapted to fit said conical bore to form an air-tight joint therebetween, and spring means for holding said valve part seated in said bore. 20
16. A machine for cementing soles to shoes comprising in combination, a jack-supporting wheel rotatably mounted and provided with an outer rim, a series of jacks each having an inflatable bag for pressing a sole against a shoe, each jack including a base plate adapted to support an inflatable bag and an integral overhanging cantilever arm for holding a shoe against the upward pressure exerted upon it when the bag is inflated, each jack being provided with a supporting bracket upon its cantilever arm that extends laterally outwardly from said arm, and means for securing the brackets to said rim so that the brackets support the jacks to project radially outwardly a substantial distance from the rim and forwardly in a plane at right angles to the plane of the wheel so that the jacks travel in a much greater circle than that defined by said rim. 30
